UNITED STATES PATENT OFFICE.

JOSEPH RAY FIFE, OF KANSAS CITY, MISSOURI.

DESIGN FOR A SHINGLE STRIP.

Application filed November 25, 1927. Serial No. 24,271. Term of patent 14 years.

To all whom it may concern:

Be it known that I, JOSEPH RAY FIFE, a citizen of the United States, residing at Kansas City, in the county of Jackson and State of Missouri, have invented a new, original, and ornamental Design for a Shingle Strip, of which the following is a specification, reference being had to the ac-

companying drawing, forming part thereof.

The figure is a plan view of a shingle strip showing my new design.

I claim:

The ornamental design for a shingle strip, as shown.

JOSEPH RAY FIFE.
